(57) **CLAIM**

We claim the ornamental design for a flash pan, as shown.

DESCRIPTION

FIG. 1 is a perspective view of the flash pan; FIG. 2 is an end view of the flash pan, the opposite end being a mirror image thereof;

FIG. 3 is a front view of the flash pan;

FIG. 4 is a top view of the flash pan;

FIG. 5 is a back view of the flash pan; and,

FIG. 6 is a bottom view of the flash pan.

The claimed design is broken near one end indicating indeterminate length.
